DESIGN FOR A SKILLET COVER

Helen E. Kavanagh, Berkeley, Calif.

Application December 19, 1939, Serial No. 89,011

Term of patent 14 years

To all whom it may concern:

Be it known that I, Helen E. Kavanagh, a citizen of the United States and a resident of the city of Berkeley, county of Alameda, State of California, have invented a new, original, and ornamental Design for a Skillet Cover, of which the following is a specification, reference being had to the accompanying drawing, forming part thereof.

Referring to the drawing:

Fig. 1 is a top plan view of the skillet cover, showing my new design.

Fig. 2 is a side elevational view of the skillet cover.

Fig. 3 is a side elevational view of the skillet cover taken at right angles to the view shown in Fig. 2.

I claim:

The ornamental design for a skillet cover, as shown.

HELEN E. KAVANAGH.
